[57] CLAIM

The ornamental design for a portable housing for a mobile telephone, radio transceiver and battery pack, substantially as shown and described.

DESCRIPTION

FIG. 1 is a front, top and right side perspective view of a portable housing for a mobile telephone, radio transceiver and battery pack showing my new design;
FIG. 2 is a left side elevation view thereof;
FIG. 3 is a rear elevation view thereof; and
FIG. 4 is a bottom plan view thereof.

FIG. 1

FIG. 2

FIG. 4

FIG. 3
